[57] **CLAIM**

The ornamental design for soap cake, as shown and described.

DESCRIPTION

FIG. 1 is an isometric view of a soap cake embodying my new design.

FIG. 2 is a plan view thereof, showing the hidden side of FIG. 1.

FIG. 3 is an elevation of the near side of FIG. 1.

FIG. 4 is an elevation of the far side of FIG. 1.

FIG. 5 is an edge view thereof, both edges of FIG. 2 being as here shown.
